UNITED STATES PATENT OFFICE.

DORCHESTER MAPES, OF CHICAGO, ILLINOIS, ASSIGNOR TO CLARENCE K. CHAMBERLAIN, OF CHICAGO, ILLINOIS.

BOOKCASE.

No. 865,114.

Specification of Letters Patent.

Patented Sept. 3, 1907.

Application filed June 7, 1906. Serial No. 320,510.

To all whom it may concern:

Be it known that I, DORCHESTER MAPES, a citizen of the United States; residing at Chicago, in the county of Cook and State of Illinois, have invented a new and 5 useful Improvement in Bookcases, of which the following is a specification.

My invention relates to furniture of the class which is formed in sections or units and which, being provided with suitable base and top, may be made of any convenient height or capacity by changing or re-arranging 10 the units of which the stack is composed. Furniture of this construction, especially when used for the storage of books is usually provided with doors which are hinged at the upper end and which when swung 15 to a horizontal position may be slid backward into a space at the upper part of the units so as to give ready access to the contents. As such doors are long and narrow the tendency thereof is to be bound by frictional contact of diagonally opposite corners with the end 20 pieces of the units.

By putting into practice the principles of my invention I am able to cause complete parallelism of movement in the doors, prevent all sticking or binding thereof, and to give them a smooth, quiet and even movement, while the devices therefor are simple, inexpensive and durable,

The principles of my invention are illustrated in the drawings, in which—

Figure 1 is a perspective view of a bookcase unit, provided with base and top—Fig. 2 is a top view of such unit with the top or cornice removed—Fig. 3 is a sectional view of Fig. 2 on the dotted line 3—3. Fig. 4 is a sectional view of Fig. 2 on the dotted line 4—4. Fig. 5 is a clip to hold the carrier rods together, and Fig. 6 35 is a fractional view of the inside of a door and an attachment therefor.

Further describing my invention with reference to the drawings: 1 is a sectional unit. 2 the base and 3 the top or cornice. The said unit is framed together 40 in the usual way, having the end pieces 4, and may be provided with a horizontal partition 5, above which is thereby formed a horizontal pocket, within which the mechanism of my device is inclosed and into which the door may be slid. In the end pieces above the partition 5, may be formed the rabbets 6, which, as a protection against wear, may be lined with sheet metal or a strip of angle iron 7. Fitted to the space or runway thus formed in the two ends is a door carrier which 45 may be of any suitable construction, but which I prefer to make as shown of a principal member or rod 10 and a hinging rod 11 which may be secured together into a substantial structure by the clips 12 and 12'. Upon the partition 5 may be mounted the small pulleys or sheaves 14 and 14' and 15 and 15'. Flexible at-

55 tachments 16—16' are passed around the said sheaves and connect the opposite ends of the carrier to each other. This flexible means of attachment may consist of any flexible material as wire or braided cable or a strong cord.

The clips by which the carrier rods are framed together may be of any suitable construction. That shown in Fig. 5 is formed of a strip of sheet metal having the ends 18 and 18' turned into tubular form to embrace the rods 10 and 11 respectively. The end 18 is somewhat broader than the other and a free portion is 65 turned down to form the lug 19, having the opening 20. These clips should preferably be formed as right and lefts.

One end of the cord or attachment 16 may be secured to the carrier by passing it through the opening 20 of 70 the clip 12, and placing a knot therein. It is then passed around the sheaves 14 and 15' and the other end secured to the right hand portion of the carrier by attaching it to the rod 11. The cord 16' is attached in like manner to the clip 12' and after passing around 75 the sheaves 14' and 15 has the free end attached to the other end of the carrier as before. When thus secured the attaching means or cords should be of substantially equal tension. When thus adjusted the carrier may be readily moved backward and forward without 80 twisting, but will retain a constant condition of parallelism of its parts with the corresponding portions of the unit on which it is mounted. It will be seen that an impulse tending to move it backward communicated to it at the right side end will be communicated 85 in equal degree to the point at which it is applied and through the medium of the attaching cord 16' to the opposite end of the carrier which is thus drawn backward at the same time that the right side is pushed backward. A similar impulse communicated to the 90 left end of the carrier will be communicated through the cord 16 to the right end of the carrier, and any impulse wherever applied will be communicated through the medium of the attaching cords, so as to balance at the ends and equalize the carrier movement.

As shown in Fig. 2 the carrier is moved partly back. A door 25 is fitted between the forwardly projecting edges 4' of the ends, and the front rod 11 of the carrier may be moved forward so as to be embedded in the groove 26 which may be formed in the upper portion 100 of the door. A clip 27 or other suitable means of attachment may be mounted on the door and by being turned over the rod 11 causes the door to be hinged thereon so as to give it a pivotal movement. When the parts are in the relative positions last described the 105 door will be closed as in Fig. 1, but upon swinging the lower part of the door forward and upward through an arc of 90 degrees it may be slid backward into the

unit, the carrier causing the several parts thereof to move in lines exactly parallel to the corresponding parts of the unit and preventing any possibility of uneven movement or binding.

5 I claim:

1. In a furniture unit, a door carrier slidably mounted therein, a door hinged to the carrier, sheaves at either end of the unit adjacent to the front edge, corresponding sheaves at the rear portion thereof, and cords passing between the front and rear sheaves and severally attached to the carrier so that an impulse given to either end of the carrier will be communicated independently thereof in the same direction to the other end of the carrier.
2. In a furniture unit, a door carrier slidably mounted therein, a door hinged to the carrier, sheaves at either end of the unit adjacent to the front edge, corresponding sheaves at the rear portion thereof, and cords passing diagonally from front to rear sheaves and severally attached to the carrier so that an impulse given to either end of the carrier will be communicated independently thereof in the same direction to the other end of the carrier.
3. In a furniture unit, a door carrier slidably mounted therein, a door hinged to the carrier, sheaves at the front corners of the unit, sheaves placed diagonally from the first mentioned sheaves, and cords passing over the sheaves and having their ends connected to the opposite ends of the carrier.
4. In a furniture unit, a door carrier slidably mounted therein, a door hinged to the carrier, a horizontal partition in the unit, sheaves at opposite corners of the partition, and a flexible connecting means passing over the sheaves and having its ends connected to the ends of the carrier.
5. In a furniture unit, a door carrier slidably mounted therein, a door hinged to the carrier, sheaves at the front and rear corners of the unit, and cords having their ends attached to opposite ends of the carrier and being intermediate passed over diagonally opposite front and rear sheaves.
6. In a furniture unit, a runway on the inner faces of the ends, a carrier adapted to move in the runway, a door pivotally attached to the carrier, a horizontal partition below the door, and means mounted on the said partition for causing the carrier to remain parallel to the front and rear edges of the unit.
7. In a furniture unit, a door carrier, guiding means therefor, a door hinged to the carrier, sheaves at opposite front and rear corners of the unit, and cords passing over the sheaves and having their ends connected to the opposite ends of the carrier.
8. In a furniture unit, a door carrier, a runway therefor, a door hinged to the carrier, sheaves at opposite front and rear corners of the unit below the runway, and cords passing over the sheaves and having their ends connected to the opposite ends of the carrier.
9. In a furniture unit, a door carrier, a runway therefor, a door hinged to the carrier, a horizontal partition below the runway, sheaves mounted at the front and rear corners of the partition, and cords passing over the sheaves

and having their ends connected to the opposite ends of the carrier.

10. In a furniture unit, a door carrier, guiding means therefor, a door hinged to the carrier, sheaves at opposite front and rear corners of the unit, and flexible connecting means passing over the sheaves and secured to the opposite ends of the door carrier, so that an impulse given to either end of the carrier will be communicated independently thereof in the same direction to the other end of the carrier.

11. A furniture unit having ends provided with runways, a plurality of rods spaced longitudinally of the unit and adapted to move in said runways and constituting a door carrier, means for securing the rods together whereby they move in unison in the runways, a door having a top rail provided with a longitudinal groove, means for securing one of said rods of the door carrier in said groove to form a pivotal connection of the door therewith, and means connected with said door carrier for maintaining the same parallel at all times with the front and rear portions of the unit.

12. A furniture unit embodying ends having runways, a plurality of rods adapted to move in said runways and constituting a door carrier, clips securing the rods of the carrier together to cause them to move in unison, a door, means for pivotally securing said door to one of the rods of said carrier, and means connected to the carrier for maintaining the same parallel at all times with the front of said unit.

13. In combination with a furniture unit having runways in the ends, and having a sliding door, a pair of rods spaced apart and secured together to slide in said runways and constituting a door carrier, means for pivotally securing the door to said carrier, and means connected to the carrier for maintaining the same parallel at all times with the front of the unit.

14. In a furniture unit having runways in the ends, a door carrier comprising a principal member and a hinging rod or member placed longitudinally of the unit, means for securing the members together, a door having a top rail with a longitudinal groove, and means for securing the hinging rod in said groove to form a pivotal connection of the door therewith.

15. In a furniture unit having runways in the ends, a door carrier comprising a principal member and a hinging member adapted to move in said runways, clips to secure the said members together, a door for the unit, and means for pivotally securing the door to one of said members.

16. In combination with a furniture unit having runways in its ends, a sliding door, a carrier slidably within the runways and comprising a principal member or rod, and a hinging rod, means for securing the member and rod together, and means for pivotally attaching the door to the hinging rod.

In witness whereof, I have hereunto set my hand, this 1st day of June A. D. 1906, in the presence of two subscribing witnesses.
